ABSTRACT OF THE DISCLOSURE

A vessel for storing high-purity and decomposable substances comprises two intercommunicating receptacles, the first of which communicates with the ambient medium and is filled with filtering and sorbing materials, preferably solids, while the second receptacle is filled with a liquid sorbent and communicates with the interior of the vessel. The second receptacle is divided by an overflow means into at least two intercommunicating chambers so that the liquid sorbent flows over from chamber to chamber when the pressure inside the vessel is balanced with respect to the outside pressure.

The present invention relates to vessels for storing substances and, more particularly, it relates to shut-off devices to be used in vessels for storing substances, mainly high-purity and decomposable substances.

The development of new fields of science and engineering has brought about an urgent need of high-purity chemical substances to be used in semiconductor, radioelectronic and nuclear industries, in the chemistry of polymers, in the production of high-purity metals and alloys, rare and trace elements, quantum generators, ion-exchange resins, catalysts, as well as in numerous other branches of science and industry.

As the requirements imposed upon high-purity substances grow more strict, special importance is attached to the problems of storing and transporting said substances, charging them into and removing from vessels, as well as of using these substances.

It is known that high-purity substances containing impurities in amounts of less than millionth or milliardth fractions of one percent become contaminated from contact with the walls of a vessel container when stored, and from contact with the environment, and become unfit for further use.

Extreme sensitivity of high-purity substances to the impurities of the container material makes apparent the maximum suitability for the above-listed purposes of substances possessing maximum homogeneity and high erosion stability. Such substances are mostly oxides of elements, e.g. of glass, in particular, quartz, glass, ceramics, polymeric materials (tetrafluoroethylene, polyethylene, vinyl chloride etc.).

When designing tare for storing said substances, provision should be made for storing therein substances decomposing under the effect of light, temperature, or because of some other reasons. Said substances, when decomposing, create considerable excessive pressures, which are likely to cause the destruction of closed vessels whose rigidity is rather low. Conventionally employed containers manufactured from the above-mentioned materials cannot withstand not only the pressure created by the decomposition of the substance but, in some cases, the difference of pressures created as a result of variations in temperature and barometric pressure.

Known hermetic shut-off devices in the form of a blind flange or ground (or screwed) stopper are unfit for use

2

with such substances and materials, since, in this case, it is necessary to balance the pressure inside and outside the vessel (container) and to provide for a thorough purification of influent and effluent media entering the vessel from the outside, without impairing the quality of the substance being stored, as well as to decontaminate the media leaving the vessel in the course of balancing the pressure.

Presently employed vessels (containers) are unsuitable for filling them with high-purity substances and for removing said substances therefrom, since their shut-off devices do not provide for the delivery into the vessel of pure air or some other outside medium for filling the vacant volume in the course of emptying the vessel and do not preclude the contact of the high-purity substance with the outside medium when charging or filling the vessel, as well as when removing and using the substance.

There is known a shut-off device capable of maintaining a constant inside pressure in the vessel with a view to preclude the destruction of the latter. This device comprises an aerosol filter arranged on the neck of the vessel and covered with a protective cap having openings for the passage of gas (cf. "Containers for Chemical Substances" by Krongaus, Moscow, 1961).

However, said known shut-off device does not fully solve the problem of purification of media entering and leaving the vessel, for it is only capable of performing the mechanical removal of particulate contaminants in gases and does not make it possible to perform their chemical purification, as well as the operations of flushing, charging, storing, transporting, removing and using the substance being preserved without impairing the quality thereof.

It is an object of the present invention to develop a shut-off filtering device for vessels, that would make it possible to perform (separately or in combination) operations of flushing, charging, storing, transporting, removing and using a high-purity substance without impairing the quality thereof, at the same time providing for the purification of media entering the vessel, decontamination of media leaving the vessel, and for balancing the inside and outside pressure with a view to precluding the destruction of said vessel.

In the accomplishment of said and other objects, in the shut-off filtering device for vessels, according to the present invention, provision is made of two intercommunicating receptacles, of which one communicates with the outside medium and is filled with filtering and sorbing materials, preferably solids, while the other receptacle is filled with a liquid sorbent and communicates with the interior of the vessel, said other receptacle being divided by an overflow means into at least two intercommunicating chambers so that the liquid sorbent flows over from chamber to chamber when the pressure inside the vessel is balanced with respect to the pressure outside said vessel.

The shut-off filtering device of the invention can be arranged outside the vessel and have a protective cap with a cone-shaped ground surface in contact with the ground surface of the neck of the vessel.

The present shut-off filtering device can have a receptacle, which communicates with the outside medium and is divided by means of partitions into a plurality of intercommunicating sections filled with filtering and sorbing materials.

The shut-off filtering device according to the invention can be fashioned so that the sections filled with filtering and sorbing materials be arranged coaxial with the chambers in which the liquid sorbent flows over.

The shut-off filtering device can be so fashioned that the last-in-row (with respect to the afflux of the outside medium into the space of the vessel) chamber of said other receptacle be connected to the outside medium via

a circular clearance, the latter being formed by the central pipe of a central connecting sleeve with openings, which pipe passes through the chambers and sections of the receptacles, without reaching the bottom of the vessel, and is connected to the internal conical wall of said connecting sleeve by means of an auxiliary pipe which is arranged coaxial with the sleeve and divides the interior of the latter into a first auxiliary chamber and a second auxiliary chamber, said second auxiliary chamber being formed by said auxiliary pipe and the conical wall of said connecting sleeve.

The shut-off filtering device of the invention can be so fashioned that, for the purposes of storing and transporting substances, onto the conical outer surface of the central connecting sleeve there is fitted a removable cap which serves to isolate the auxiliary chambers from the outside medium and communicates via an opening said first auxiliary chamber with said second auxiliary chamber, which latter chamber receives through an opening the purified outside medium directed via an opening into the interior of the vessel through a hydraulic seal formed by the clearance between the auxiliary pipe and the central connecting sleeve, a clearance between the walls of the lower and upper bodies of the device, and pipes interconnecting said clearances, said hydraulic seal serving to isolate the interior of the vessel from the outside medium.

The shut-off filtering device can be fashioned so that, for the purposes of flushing the internal surface of the vessel and filling the latter with a substance, onto the conical outer surface of the central pipe of the central connecting sleeve there is fitted an attachment including a bypass cock and a coupling connected thereto and adapted to isolate the first auxiliary chamber from the outside medium and from the second auxiliary chamber connected to the bypass cock which, in its turn, is connected to the inlet end of said central pipe.

The present shut-off filtering device can be fashioned so that, for the purposes of removing substances from the vessel and using them, onto the conical outer surface of the central pipe of the central connecting sleeve there is fitted an attachment including a calibrated burette with a shut-off filtering means to which burette there is connected a pipe union with a coupling, said coupling serving to isolate the auxiliary chambers from the interior of the central pipe and connect both said auxiliary chambers to each other and to the interior of the vessel.

The shut-off filtering device according to the present invention can be fashioned so that the sections filled with filtering and sorbing materials are positioned above the chambers in which flows the liquid sorbent.

The shut-off filtering device can be arranged inside the vessel, the central connecting sleeve being passed through said filtering device towards the bottom of the vessel without touching said bottom.

The shut-off filtering device can be so fashioned that, for the purpose of disconnecting the space of the vessel from the receptacles, the upper end of the overflow means is provided with a ground surface mating with a corresponding ground surface of the connecting sleeve by mutual axial displacement of said overflow means and connecting sleeve of the neck of the vessel in the course of flushing and filling the vessel.

The shut-off filtering device can be fashioned so that the sections of said first receptacle filled with filtering and sorbing materials are positioned above said other receptacle in which the chambers with the liquid sorbent flowing therein are arranged coaxially.

For the purpose of disconnecting the interior of the vessel from the device and from the outside medium, the shut-off filtering device can be fitted with a connecting sleeve of the neck of the vessel, which connecting sleeve is provided with a circular sealing projection connectable by mutual axial displacement with a projection of a part and an auxiliary pipe when flushing and filling the vessel.

The shut-off filtering device of the present invention can

70

be fashioned as a body having flanged edges and a cover including a circular projection, which are mated with each other and with the neck of the vessel during the mutual turn of the cover and the body when flushing and filling the vessel, for the purpose of isolating the interior of said vessel from the receptacles and the outside medium.

The shut-off filtering device can be so fashioned that, for the purposes of storing and transporting substances, onto the conical outer surface of the central pipe of the central connecting sleeve there is fitted a removable cap serving to isolate said second auxiliary chamber from the outside medium.

The shut-off filtering device can be so fashioned that, for the purposes of flushing the internal surface of the vessel with a high-purity substance and filling it with same, onto the conical outer surface of the central pipe of the central connecting sleeve there is fitted an attachment including a bypass cock and a coupling connected thereto and adapted to isolate from the outside medium said second auxiliary chamber connected by means of a side pipe with the bypass cock which, in turn, is connected to the inlet cone of said central pipe.

The present shut-off filtering device can be fashioned so that, for the purposes of removing substances from the vessel and using them, onto the conical outer surface of the central pipe of the central connecting sleeve there is fitted an attachment including a calibrated burette with a shut-off filtering means, to which burette there is connected a pipe union with a coupling, said coupling serving to isolate said second auxiliary chamber from the interior of the central pipe.

Therefore, the employment of the present invention makes it possible to store and transport high-purity substances, charge them into and remove from tare, as well as to use high-purity substances, such as nitric and various other acids, water, metal, alkali, carbon and other organic and inorganic, liquid and solid high-purity substances.

Other objects and advantages of the invention will become apparent from the following description in connection with which certain preferred embodiments of the invention have been shown with due reference to the accompanying drawings, in which:

FIG. 37 shows two sections XXXVII—XXXVII, defined by parallel planes in FIG. 35, conventionally turned through 90°;

FIG. 38 illustrates the shut-off filtering device, as shown in FIG. 31, on which there is fitted an attachment adapted for removing the high-purity substance from the vessel into a burette;

FIG. 39 illustrates the position of the burette and conduits of the shut-off filtering device, as shown in FIG. 38, following the removal of the high-purity substance from the burette.

Now, referring to the drawings, FIG. 1 is a basic diagram of the present shut-off filtering device secured by means of a union 13 to a neck 2 of a vessel 1.

The device according to the invention includes two receptacles, one 21 and the other 12. The receptacles are separated from each other by means of a partition 15 and communicate via an opening 14. Onto the partition 15 there is placed a hydrophobic separator 16 followed by filtering materials 17 and, further, by sorbing materials 18 divided by means of partitions 19 and exposed to sections 20. At the outlet into the environment the first receptacle 21 is closed with filtering materials 23 held in place by a union 22.

The second receptacle 12 is, in turn, divided by means of a partition 10 into at least two chambers, a first chamber 11 and a second one 7 with a dead-end bottom 3. The first chamber 11 is connected via the opening 14 to the first receptacle 21 and, via an opening 9 and an overflow means 6 having an opening 4, communicating with chamber 7. The chamber 7 is connected through an opening 8 to the working space or annular chamber of the vessel 1. One of the chambers 7 or 11 is filled with a liquid sorbent 5 flowing over from chamber to chamber when the pressure in the working space of the vessel 1 is balanced with respect to the pressure outside said vessel.

The shut-off filtering device of the present invention operates in accordance with the following principle.

When the pressure inside the vessel is reduced (as a result of a temperature decrease, increase of barometric pressure, emptying the vessel etc.), the outside medium enters the first receptacle 21 (the direction of movement of said outside medium shown by a continuous arrow) where it is rendered free of mechanical impurities with the aid of the filtering materials 23 and purified from chemical impurities with the aid of the sorbing materials 18 and, further, with the filtering materials 17, to prevent the sorbents from passing into the other receptacle 12.

From the first receptacle 21 the outside medium passes via the opening 14 into the first chamber 11 of the other receptacle 12, forcing the liquid sorbent 5 from the first

chamber 11 into the chamber 7 through the openings 9 and 4. After being cleaned in the chamber 7 from the remaining mechanical and chemical impurities in the course of bubbling, saturation and sorption, said outside medium passes into the working space of the vessel 1 through the opening 8.

In case the pressure in the working space of the vessel 1 exceeds that outside the vessel, gas-vapor mixture from the space of the vessel 1 passes via the opening 8 into the chamber 7 of the other receptacle 12, forcing the liquid sorbent 5 via the overflow means 6 into the first chamber 11 (the direction of movement of the gas-vapor mixture shown by a broken arrow, and the position of the liquid sorbent 5 in the chamber 11—by a broken line). Retracting with the liquid sorbent 5 in the other receptacle 12 and with the sorbing materials in the sections 20 of said first receptacle 21, gases are decontaminated and let out into the environment through the filtering materials 23.

The shut-off filtering device according to the present invention is universal, for it facilitates the variation of relative amounts of filtering and sorbing liquid and solid materials, as well as the selection of said materials as to quality and volume, depending upon the individual properties of a substance being preserved and outside medium.

When using different sorbing materials which are not to be mixed together, said sorbing materials are either separated by insulating layers of filtering materials, or they are placed into bags manufactured from filtering materials; the bags are arranged in the required pattern in the first receptacle 21.

Examples of suitable solid and liquid filtering materials include aerosol filters, selective sorbents, chemical absorbents and other substances, including the substance being preserved, which effect chemical reaction, electrostatic, mechanical and other types of sorption, filtration, extraction and purification from impurities until the impurity content in the outside medium entering the working space of the vessel is less than or equal to that of the substance being stored in the vessel.

The shut-off filtering device of the present invention makes it possible to determine the pressure inside the vessel with respect to the outside medium by the position of the liquid sorbent 5 in the chambers of the other receptacle 12 and the direction of movement of gases and vapors passing through the bubbling stage.

Shown in FIG. 2 is a shut-off filtering device disposed outside the vessel 1a and joined thereto with the aid of ground surfaces. This latter device differs from the device shown in FIG. 1 by that it is installed on the neck 2a of the vessel 1a, provided with two cones having ground surfaces, 26a and 29a, of smaller and greater diameter, respectively; the first receptacle 21a terminates below a partition 15a with a ground coupling 25a set on a ground cone 26a which above the neck 2a of the vessel 1a; on a greater ground cone 29a there is set a protective cap 24a with a ground coupling 28a and opening 27a through which circulate the outside medium entering the vessel 1a through the shut-off device and decontaminated gases leaving said vessel.

Following is the operational procedure of the shut-off filtering device according to the present invention.

When the pressure inside the vessel 1a is reduced, the outside medium enters via the opening 27a in the protective cap 24a onto filtering materials 23a where it is purified from mechanical impurities and sols (the movement of said medium shown by arrow). Then, the outside medium passes in the radial direction from the center to the periphery and back (for a fuller utilization of the sorbents) through sections 20A of the first receptacle 21a, which are separated from each other by means of the partitions 19a and are filled with the sorbing materials 18a, where it is purified from chemical and mechanical impurities.

After having passed the filtering materials 17a, which prevent the traces of the sorbing materials 18a from leav-

ing said first receptacle 21a, the outside medium passes into the other receptacle 12a, where it forces liquid sorbent 5a from the first chamber 11a into the chamber 7a via the overflow means, bubbles through said liquid sorbent, is washed from traces of impurities and, via opening 8a, enters the interior of the vessel 1a.

When the pressure inside the vessel 1a exceeds that of the outside medium, gas-vapor mixture (the movement of gas-vapor mixture shown by broken arrow) enters via the opening 8a of the chamber 7a, the other receptacle 12a and forces the liquid sorbent 5a via the overflow means 6a into the first chamber 11a (the position of said liquid sorbent 5a in the chamber 11a shown by broken line). Reacting with the liquid sorbent 5a and with sorbing materials 18a in the first receptacle 21a, decontaminated gases are let out into the environment through the filtering materials 23a and the opening 27a in the protective cap 24a.

Shown in FIGS. 3, 4, 7, 10, 12, 13, 16, 19, 21, 22, 23, 26, 29, 31, 32, 35 and 38 are shut-off filtering devices, according to the present invention, to be arranged inside the vessel together with attachments adapted for storing and transporting high-purity substances (FIGS. 3, 12, 21, 22, 31), for flushing the internal surface of the vessel 1b, e, h, and l (FIGS. 4, 13, 23, 32), for filling the vessel 1b, e, h and l with a high-purity substance (FIGS. 7, 16, 26, 35) and for removing from the vessel 1b, e, h and l and using said high-purity substance (FIGS. 10, 19, 29, 38) without impairing the purity thereof.

Since the shut-off filtering devices designed for storing and transporting (FIG. 3), flushing and filling (FIGS. 4, 7) removing and using (FIG. 10) high-purity substances differ from each other by attachments alone (24b, 46c, and 65d), only a detailed description of the shut-off filtering device according to (FIG. 3) is presented herein. With reference to FIGS. 4, 7 and 10, only the operation of those parts of the present shut-off filtering device is described in detail, which take part in the operation of particular attachments.

On the other hand, the shut-off filtering devices, as shown in FIGS. 3, 12, 21, 22 and 31, in FIGS. 4, 13, 23, and 32, in FIGS. 7, 16, 26 and 35, and in FIGS. 10, 19, 29 and 38, are different for each group of figures, however, for performing similar operations the same attachments are used. Therefore, the descriptions of separate attachments are not repeated, although they are defined by different reference numerals.

The shut-off filtering device (FIG. 3) is set by means of a coupling 25b on a ground cone 26b which is above the neck 2b of the vessel 1b. Said device consists of an upper body 37b and lower body 43b. The coupling 25b is connected to the upper body 37b having along the circumference thereof openings 8b. In turn, the upper body 37b is overlappingly joined (forming an effective clearance 42b) to the lower body 43b having a bottom 3b which does not touch a bottom 45b of the vessel 1b, and a central connecting sleeve 38b in the form of a central pipe 31b hermetically sealed by a plug 30b, and a ground cone 29b.

Coaxial with the central pipe 31b in the body of the shut-off filtering device there is installed an auxiliary pipe 40b, whose lower end terminates with a partition 10 and an overflow means 6b (in the form of a cap) forming with the lower body 43b and its bottom 3b clearances, 9b and 4b, respectively.

The space under the cap 6b forms the chamber 7b of second receptacle 12b, filled with the liquid sorbent 5b. Secured to the auxiliary pipe 40b above the partition 10b is a horizontal partition 15b which forms with the lower body 43b a minimal clearance 14b.

The space defined by the lower body 43b, partition 10b of the overflow means 6b and the partition 15b forms the first chamber 11b of said second receptacle 12b. The volume of the first chamber 11b should not be smaller than that the chamber 7b.

The space above the horizontal partition 15b, defined by the lower body 43b and connected to the environment via the upper body 37b, forms the first receptacle 21b successively filled with bags made from filtering materials 17b and containing sorbing materials 18b, tightly fitting the lower body 43b of the shut-off filtering device.

To the upper end of the central pipe 31b of the connecting sleeve 38b there is connected the ground cone 29b of the latter connecting sleeve, connected to the auxiliary pipe 40b. The upper end of the auxiliary pipe 40b is joined to the inner side of the ground cone 29b and divides the space defined by said latter cone and the central pipe 31b into two auxiliary chambers; the first, 32b, and the second, 36b. The first auxiliary chamber 32b communicates with the environment through openings 33b and 35b; and the second auxiliary chamber 36b—through an opening 34b.

A circular clearance 39b defined by the auxiliary pipe 40b and cone 29b with a pipe union is communicated by means of at least two pipes 41b with the circular clearance 42b and, via openings 8b—with the interior of the vessel 1b.

The hydraulic seal, formed by the pipes 41b, circular clearances 39b and 42b and the liquid sorbent 5b, prevents the high-purity substance in the vessel from immediate contact with the outer medium via the openings 33b, 34b and 35b.

For the purposes of storing and transporting the high-purity substance in the vessel 1b without impairing the quality of said substance, the central pipe 31b is sealed hermetically by means of the plug 30b; then, a cap 24b with a coupling 28b is set on the ground cone 29b, thereby providing for the intercommunication of the auxiliary chambers 32b and 36b via the openings 33b, 34b and 35b, as well as for the isolation of said auxiliary chambers from the outside medium.

When the pressure inside the vessel 1b is reduced, the outside medium enters, via the circular space defined by the upper body 37b and the cap 24b, the first receptacle 21b (the movement of the outside medium shown by arrow), and filters through the bags of the filtering materials 17b filled with the sorbing materials 18b, wherein said outside medium is purified from mechanical and chemical impurities. Then, the outside medium passes through the clearance 14b into the first chamber 11b of the other receptacle 12b, forces the liquid sorbent 5b via the overflow means 6b into the last chamber 7b of the other receptacle 12b, is flushed free of the reacts of impurities in the process of bubbling, and passes up through a circular clearance 44b into the first auxiliary chamber 32b. After having left the latter chamber through the openings 33b and 35b and passed under the cap 24b through the opening 34b into the second auxiliary chamber 36b, the purified outside medium forces the liquid sorbent 5b from the circular clearance 39b and pipes 41b into the circular clearance 42b and, via the openings 8b, enters the interior of the vessel 1b, thus balancing the inside pressure with that of the outside medium.

Upon the increase of pressure inside the vessel 1b the gas-vapor mixture travels the above-described path in the reverse sequence (the movement of the gas-vapor mixture shown by broken arrow), that is, the gas-vapor mixture enters via the openings 8b the circular clearance 42b, and forces the liquid sorbent 5b via the pipes 41b into the circular clearance 39b; bubbling through the liquid sorbent 5b, the gas-vapor mixture goes into the secondary auxiliary chamber 36b and leaves the latter via the opening 34b for the cap 24b; thereupon, the mixture enters via the opening 35b the first auxiliary chamber 32b, passes down through the circular clearance 44b into the chamber 7b, forces the liquid sorbent 5b from the latter chamber 7b into the first chamber 11b of the second receptacle 12b (the position of the liquid sorbent 5b in the chamber 11b shown by broken line), and bubbles through said liquid sorbent; reacting with the liquid sorbent 5b, sorbing ma-

terials 18b and filtering materials 17b, disposed in the first receptacle 21b, decontaminated gases leave into the outside medium, thus balancing the pressure on both sides of the walls of the vessel 1b.

FIG. 4 illustrates the shut-off filtering device, as shown in FIG. 3, on which there is fitted (in the position shown in FIG. 5) an arrangement 46c adapted for flushing with a high-purity substance the internal surface of the vessel 1b.

The attachment 46c is essentially a cock 51c connected to a coupling 47c adapted to be set on the ground cone 29b of the shut-off filtering device of the vessel 1b. The cock 51c, including a body 52c and a plug 53c, combines two three-way cocks 59c and 60c (FIG. 5). The body 52c of the cock 51c is provided with six conduits: the first conduit 49c communicates the body 52c with the coupling 47c on a level with the opening 34b of the cone 29b; the second conduit 48c, communicating the body 52c of the cock 51c with the coupling 47c, enters the central pipe 31b of the shut-off filtering device. Arranged on the body 52c, diametrically opposite relative to the conduits 48c and 49c and on the same axis with the latter conduits, are the third conduit 56c and the fourth, 57c, which are interconnected by means of a manifold 58c adapted for supplying the high-purity substance. The fifth conduit 54c is arranged normal to the axis of the conduits (pipes) 49c and 56c of the cock 60c, while the sixth conduit 55c is arranged normal to the axis of the conduits (pipes) 48c and 57c of the cock 59c on the side opposite relative to the conduit 54c. The conduits 54c and 55c are interconnected by means of a manifold 50c adapted for removing the gas-vapor mixture and gas-vapor-liquid emulsion.

The coupling 47c is provided with two openings, 61c and 62c (FIG. 6). These latter openings are connected by means of a conduit 63c to each other and to a conduit 64c which serves to communicate the conduit 63c with the interior of the central pipe 31b (FIG. 4).

When the openings 61c and 62c coincide with the openings 34b and 35b, the purified outside medium passes inside the vessel 1b and the central pipe 31b via the conduits 63c and 64c, the inside pressure being balanced with that of the outside medium.

When flushing the internal surface of the vessel 1b, the plug 53c of the cock 51c is shifted to the position as in FIG. 5, which shows two sections V—V of the cock 51c, defined by two parallel planes in FIG. 4, conventionally turned through 90°. When so doing, the openings 34b and 35b are in the position as shown in FIG. 6. In this position, the high-purity substance via the manifold 58c, conduit 56c, plug 53c, conduit 49c and the opening 34b goes into the circular clearance 39b (the movement of the high-purity substance shown in FIGS. 4 and 5 by arrow). From here, the high-purity substance passes via the pipes 41b into the circular clearance 42b, is poured via the openings 8b onto the neck 2b of the vessel 1b, are spread throughout the internal surface of the vessel 1b thus flushing the same. As the substance accumulates on the bottom 45b of the vessel 1b, it is sucked in the form of a gas-vapor-liquid emulsion along the central pipe 31b into the conduit 48c and, via the conduit in the plug 53c of the cock 51c, and the conduit 55c, enters the manifold 50c (the movement of the emulsion shown in FIGS. 4 and 5 by broken arrow).

In order to remove the vessel 1b after flushing the internal surface thereof, the cock 51c is cut off the conduits 48c, 49c and 56c, 57c; the attachment 46c is set into position as shown in FIG. 9. As a result, the outside medium purified in accordance with the technique disclosed in the description of FIG. 1 passes inside the central pipe 31b and the vessel 1b via the openings 34b, 35b, 61c and 62c, the conduits 63c and 64c, thus balancing the inside pressure with that of the outside medium.

FIG. 7 illustrates the shut-off filtering device on which there is fitted (in the position shown in FIG. 8) the attachment 46c adapted for filling the vessel 1b with a high-purity substance.

Since the only difference of the flushing process from the filling one resides in the position of the conduits in the plug 53c of the cock 51c (FIG. 8), all the reference numerals in FIGS. 4, 5 and 6 remain completely the same for defining the respective positions in FIGS. 7, 8 and 9.

For filling the vessel 1b with a high-purity substance, the plug 53c of the cock 51c is shifted, by turning it through 90°, into position as in FIG. 8. FIG. 8 shows two sections VIII—VIII of the cock 51c, defined by parallel planes in FIG. 7, conventionally turned through 90°. The openings 34b and 35b are, at the same time, in the position shown in FIGS. 4, 6 and 7.

In this position, the high-purity substance via the manifold 58c, conduit 57c, conduit of the plug 53c and conduit 48c goes along the central pipe 31b into the working space of the vessel 1b, thus filling the latter (the movement of the high-purity substance shown in FIGS. 7 and 8 by arrow).

Air and vapors are sucked from the vessel 1b through the openings 8b, circular clearance 42b, pipes 41b, circular clearance 39b, via the opening 34b, along the conduit 49c, conduit in the plug 53c of the cock 51c and conduit 54c into the manifold 50c (the movement of gases and vapors shown in FIGS. 7 and 8 by broken arrow).

After filling the vessel 1b with the high-purity substance, the pressure inside the central pipe 31b and vessel 1b should be balanced with that of the outside medium. To this end, the cock 51d is cut off the conduits 48c, 49c and 50c, 57c; the ground cone 29b (or coupling 47c) is turned through 90° until the openings 34b and 35b of the cone 29b coincide with those 61c and 62c of the coupling 47c (FIG. 9, section on the line IX—IX). As a result, the outside medium purified in accordance with the technique disclosed in the description of FIG. 1 passes inside the central pipe 31b and vessel 1b via the openings 34b, 35b, 61c, and 62c, the conduits 63c and 64c, thus balancing the inside pressure with that of the outside medium.

FIG. 10 illustrates the shut-off filtering device, as shown in FIG. 3, on which there is fitted an attachment 65d adapted for removing the high-purity substance from the vessel 1b into a burette 75d.

The attachment 65d is essentially a calibrated burette 75d, whose spout 76d is disposed inside a pipe union 77d connected with a coupling 78d, said latter coupling being ground to fit the surface of the cone 29b and having on a level with the openings 34b and 35b a connecting circular space 79d. Thus, the interior of the central pipe 31b is isolated from the outside medium, whereas the interior of the vessel 1b communicates with the outside medium via the shut-off filtering device. Connected with the coupling 78d on a level with the opening 33b is a conduit 80d (FIG. 11), which connects the first auxiliary chamber 32b with the interior of the central pipe 31b when the attachment 65d is turned through 90°.

The upper portion of the burette 75d is essentially a shut-off filtering means separated from the interior of the burette by means of a horizontal partition 15d, to which there is connected a bottom chamber 7d of a second receptacle 12d, having an opening 8d serving to communicate the interior of the burette 75d with the last chamber 7d.

In the center of the partition 15d there is mounted an overflow means 6d which intercommunicates via openings 9d and 4d a first chamber 11d and the last chamber 7d of the second receptacle 12d of said shut-off filtering means. The bottom end of the overflow means 6d is lowered to the bottom of the last chamber 7d without touching said bottom.

The top end of the first chamber 11d of the second receptacle 12d terminates with a funnel 14d closed by filtering materials 17d kept in place with the aid of a bracing 22d.

Connected to the burette above the partition 15d is a first receptacle 21d terminating with a ground coupling 75

69d provided with a pipe 71d which communicates the burette 75d with the environment or with a vacuum line. To the first receptacle are poured sorbing materials 18d covered with filtering materials 23d.

5 The coupling 69d receives a ground cone 68d having an opening 70d and handle 66d. To the latter handle there is joined, coaxial with the cone 68d, a cylinder 73d adapted to be pressed into the filtering materials 23d and sorbing materials 18d as well as to preclude direct communication of the second receptacle 12d with the outside medium.

In order to remove from the vessel 1b the high-purity substance, the burette 75d together with the ground coupling 78d connected thereto is set onto the ground cone 29b of the shut-off filtering device of the vessel 1b. When so doing, the spout 76d of the burette 75d pierces the plug 30b and is received by the central pipe 31b of the shut-off filtering device of the vessel 1b. Thereupon, a vacuum line is connected to the pipe 71d, and there takes place the evacuation of the interior space of the burette 75d and of the central pipe 31b of the shut-off filtering device of the vessel 1b through the shut-off filtering means of the burette 75d. As a result, the outside medium purified in the shut-off filtering device of the vessel 1b in a manner described hereinabove (cf. description of FIG. 3), after having passed inside the vessel through the openings 8b, forces the contents of the vessel 1b through the central pipe 31b into the burette 75d (the movement of gases and vapors shown in FIG. 10 by arrow).

30 Gases and vapors from the central pipe 31b and burette 75d via the opening 8d pass into the last chamber 7d of the shut-off filtering means of the burette 75d and force the liquid sorbent 5d via the overflow means 6d into the first chamber 11d.

35 In the process of contacting the liquid sorbent 5d, filtering materials 17d and 23d, and sorbing materials 18d, the gases and vapors are decontaminated and, via the opening 70d in the ground cone 68d and coupling 69d and along the pipe 71d, are sucked out into the vacuum system.

40 After the burette 75d is filled, the opening in the coupling 69d is closed with the surface of the cone 68d by turning the handle 66d.

45 For removing the burette 75d from the cone 29b of the shut-off filtering device of the vessel 1b, said burette is turned through 90° until the opening 33b on the cone 29b is aligned with the conduit 80d in the coupling 78d (FIG. 11); at the same time, the interior spaces of the pipe union 77d of the burette 75d and of the central pipe 31b of the shut-off filtering device are filled with purified outside medium supplied from the first auxiliary chamber 32b through the opening 33b in the cone 29b of the shut-off filtering device of the vessel 1b until the inside pressure is balanced with that of the outside medium (the movement of the purified outside medium shown in FIG. 11 by arrow).

60 When emptying the burette 75d for the purpose of using the high-purity substance, the opening 70d in the cone 68d is aligned with that in the coupling 69d. When so doing, the outside medium (its movement shown by broken arrow) along the pipe 71d passes through a circular clearance 72d into the first receptacle 21d of the shut-off filtering device, and filters through the filtering materials 23d and sorbing materials 18d in its way down on the outer side of the cylinder 73d and then up on the inner side of the cylinder 73d, being purified from mechanical and chemical impurities.

65 Passing up a circular clearance 67d towards the top funnel 14d of the first chamber 11d of the second receptacle 12d, the purified outside medium forces the liquid sorbent through the opening 9d, overflow means 6d and opening 4d into the last chamber 7d (the position of the liquid sorbent shown by broken line), is purified from the traces of impurities in the course of bubbling and, via the openings 8d, passes inside the burette 75d, balancing the pres-

sure inside the latter with that of the outside medium. Thereupon, the high-purity substance is fed under static pressure through the spout 76d for being used.

FIG. 12 illustrates the shut-off filtering device disposed inside the neck 2e of the vessel 1e, wherein sections 20e of the first receptacle 21e filled with filtering materials 17e and 23e and sorbing materials 18e are arranged coaxial with chambers 7e and 11e of the other receptacle 12e, in which the liquid sorbent 5e flows over. The top end of the neck 2e of the vessel 1e has flanged edges 86e and a connecting sleeve 88e which terminates at its top with a ground conical surface 85e, while its lower end is provided with a bottom 3e connected to the body of the vessel 1e. The circular space defined by the neck 2e and the connecting sleeve 88e forms the second receptacle 12e of the shut-off filtering device. Mounted on shock absorbers 93e on the bottom 3e of the connecting sleeve 88e is the first receptacle 21e of the shut-off filtering device. This latter receptacle is essentially a sleeve 89e having flanged edges and a conical bottom 94e to which there is connected a central connecting sleeve 38e in the form of an expander 87e, a ground cone 29e connected thereto and having openings 33e and 34e, and a central pipe 31e lowered to the bottom 45e of the vessel 1e without touching said bottom. The cone 29e has an elongated end with the flanged edges 86e over which there is pulled a film 30e secured by means of a thread 22e. The space defined by the central pipe 31e, cone 29e and the expander 87e forms a second auxiliary chamber 36e. Joined to the central pipe 31e is a cone-shaped plate 95e having flanged edges and adapted to receive the conical bottom 94e of the sleeve 89e of the first receptacle 21e of the shut-off filtering device to form a hydraulic seal with the liquid sorbent 5e, whereby there is precluded a direct communication of the outside medium with the interior of the vessel 1e through the openings 33e and 34e following the removal of a cap 24e. To the sleeve 89e there is joined an overflow means 6e in the form of a cylindrical collar terminating on top with a ground internal surface 84e (on the coupling) and having on the side surface and on the bottom end pins 92e (at least three pins) adapted for securing thereon the shock absorbers 93e resting against the bottom 3e of the connecting sleeve 88e and against the neck 2e of the vessel 1e. The cylindrical portion of the overflow means 6e serves to divide the second receptacle 12e into two chambers, the first 11e and the second 7e, in which chambers the liquid sorbent 5e flows over from chamber to chamber. Inside the sleeve 89e and coaxial with the central connecting sleeve 38e there is mounted a cylinder 82e. Into the circular space defined by the sleeve 89e and cylinder 82e are poured the sorbing materials 18e divided by means of partitions 19e into the sections 20e. The cylinder 82e is provided on the bottom with grooves 90e, and on top—with two circular recesses 81e, adapted to receive the thread 22e securing the inner ends of the filtering materials 17e and 23e and of a sealing film 83e. The outer ends of the filtering materials 17e and 23e are pulled and secured on the flanged edges of the sleeve 89e while the outer end of the sealing film 83e is tightly pulled over the flanged edges 86e of the neck 2e of the vessel 1e and secured thereon by means of the thread 22e.

For the purposes of storing and transporting the high-purity substance in the vessel 1e without impairing the quality of said substance, the central pipe 31e is hermetically sealed with the film 30e secured by means of the thread 22e; then, onto the ground cone 29e there is set the cap 24e with a ground coupling 28e isolating the openings 33e and 34e of the second auxiliary chamber 36e from the outside medium.

Following the reduction of pressure inside the vessel 1e, the outside medium (the direction of movement of the latter shown by arrow) passes through the filtering materials 23e to the interior of the cylinder 82e and is purified from mechanical impurities; having passed through a clearance 98e via the grooves 90e, the outside medium

is purified from mechanical and chemical impurities by the sorbing materials 18e, disposed in the sections 20e of the first receptacle 21e, and then by the filtering materials 17e, whereupon said outside medium enters the second receptacle 12e in which it forces the liquid sorbent 5e via the overflow means 6e from the first chamber 11e into the chamber 7e. The purified outside medium, which in the course of bubbling through the liquid sorbent 5e has been washed from the traces of impurities, passes through a clearance 8e between a coupling 84e and the cone 85e and a clearance 91e, formed by the connecting sleeve 88e and the sleeve 89e, into the interior of the vessel 1e, whereby the pressure inside the latter is balanced with that of the outside medium.

In case the pressure inside the vessel 1e exceeds that of the outside medium, the gas-vapor mixture travels the above-described path in the reverse sequence (the movement of the gas-vapor mixture shown by broken arrow), that is, the gas-vapor mixture going up the clearance 91e enters through the clearance 8e the chamber 7e and forces the liquid sorbent 5e into the chamber 11e (the position of the liquid sorbent shown by broken line). Reacting with the liquid sorbent 5e, filtering materials 17e, sorbing materials 18e, decontaminated gases leave through the filtering materials 23e into the outside medium.

FIGS. 13, 14, 15 and 16, 17, 18 illustrate the shut-off filtering device, as shown in FIG. 12, on which there is fitted an attachment 46f adapted for flushing the internal surface of the vessel 1e with a high-purity substance (FIGS. 13, 14 and 15) and for filling the vessel 1e with high-purity substance (FIGS. 16, 17 and 18).

The attachment 46f being essentially the attachment 46c described hereinabove in connection with FIGS. 4, 5, 6, 7, 8 and 9, presented hereinbelow is the description of only those elements of the attachment which take part in the operation of the shut-off filtering device when flushing and filling the vessel 1e with a high-purity substance.

For the purpose of flushing the internal surface of the vessel 1e, pressure is applied by means of the attachment 46f (or, on the contrary, by means of the vessel 1e) through the cone 29e of the central connecting sleeve 38e onto the shock absorber 93e, and the coupling 84e of the overflow means 6e is tightly fitted on the ground cone 85e of the connecting sleeve 88e. The attachment 46f being locked in this position, the interior of the vessel 1e is fully disconnected from the outside medium. Then, a plug 53f of a cock 51f is shifted to the position as in FIG. 14, which shows two sections XIV—XIV of the cock 51f defined by parallel planes in FIG. 13, conventionally turned through 90°. When so doing, the opening 34e is in the position shown in FIG. 15. In this position, the high-purity substance via manifold 58f, conduit 56f, plug 53f, conduit 49f and opening 34e goes into the second auxiliary chamber 36e whence, filling conduits 97e and 96e and a plate 95e the high-purity substance flows over the edges of said latter chamber onto the walls of the sleeve 89e and further, along the bottom 3e of the latter, onto the walls of the vessel 1e (the movement of the high-purity substance shown in FIGS. 13 and 14 by arrow).

As the substance accumulates on the bottom 45e of the vessel 1e, it is sucked in the form of a gas-vapor-liquid emulsion along the central pipe 31e into a conduit 48f and, via the conduit in the plug 53f of the cock 51f and a conduit 55f, enters a manifold 50f (the movement of emulsion shown in FIGS. 13 and 14 by broken arrow).

FIG. 16 illustrates the shut-off filtering device according to FIG. 12, on which there is fitted (in the position shown in FIG. 18) the attachment 46f adapted for filling the vessel 1e with a high-purity substance.

Since the only difference of the flushing process from the filling one resides in the position of conduits in the plug 53f of the cock 51f with respect to conduits in a body 52f of said cock (FIG. 18), all the reference numerals in FIGS. 13, 14 and 15 remain completely the same for defining the respective positions in FIGS. 16, 17 and 18.

For filling the vessel 1e with a high-purity substance, the plug 53f of the cock 51f is shifted, by turning it through 90°, into position as shown in FIG. 18. FIG. 18 shows two sections XVIII—XVIII of the cock 51f, defined by parallel planes in FIG. 16, conventionally turned through 90°. The opening 34e is, at the same time, in the position as shown in FIGS. 13, 14, 15 and 16.

In this position, the high-purity substance via the manifold 58f, a conduit 57f, conduit of the plug 53f and conduit 48f passes along the central pipe 31e to the interior of the vessel 1e, thus filling the latter (the movement of the high-purity substance shown in FIGS. 16 and 18 by arrow).

Air and vapors are sucked from the vessel 1e through clearances 96e and 97e, opening 34e, along the conduit 49f, conduit in the plug 53f of the cock 51f and conduit 54f into the manifold 50f (the movement of gases and vapors shown in FIGS. 16 and 18 by broken arrow).

After filling the vessel 1e with the high-purity substance, the pressure inside the central pipe 31e and vessel 1e should be balanced with that of the outside medium, for the purpose of removing the vessel 1e. To this end, the conduits 48f, 49f, 56f and 57f are closed from each other by means of the plug 53f of the cock 51f; the attachment 46f is released and, by being turned through 90°, is shifted to the position as shown in FIG. 17. The shock absorbers 93e, expanding, cause the communication of the first receptacle 21e with the overflow means 6e, disconnecting the coupling 84e from the cone 85e with a subsequent re-establishment of the clearance 8e. As a result, the outside medium purified in accordance with the technique disclosed in the description of FIG. 12 passes via the clearances 8e and 91e to the interior of the vessel 1e, and via the clearances 96e and 97e (forcing, at the same time, into the expander 87e the liquid sorbent 5e, whose position is shown in FIG. 16 by broken line), openings 34e and 61f, conducts 63f, 64f enters the interior of the central pipe 31e, thus balancing the pressure inside said vessel and central pipe with that of the outside medium.

FIG. 19 illustrates the shut-off filtering device, as shown in FIG. 12, on which there is fitted an attachment 65g adapted for removing the high-purity substance from the vessel 1e into a burette 75g.

Since the attachment 65g is essentially the attachment 65d described hereinabove in connection with FIGS. 10 and 11, presented hereinbelow is the description of only those elements of the attachment which take part in the operation of the shut-off filtering device when removing and using the high-purity substance.

In order to remove from the vessel 1e the high-purity substance, the burette 75g together with a ground coupling 78g connected thereto is set onto the ground cone 29e of the shut-off filtering device of the vessel 1e. When so doing, a spout 76g of the burette 75g pierces the film 30e and is received by the central pipe 31e of the shut-off filtering device of the vessel 1e. Thereupon, a vacuum line is connected to a pipe 71g, and there takes place the evacuation of the interior spaces of the burette 75g and of the central pipe 31e of the shut-off filtering device of the vessel 1e through a shut-off filtering means of the burette 75g. As a result, the outside medium purified in the shut-off filtering device of the vessel 1e in a manner described hereinabove (cf. description of FIG. 12), after having passed inside the vessel through the clearances 8e and 91e, forces the contents of the vessel 1e through the central pipe 31e into the burette 75g (the movement of gases and vapors shown in FIG. 19 by arrow).

Gases and vapors from the central pipe 31e and burette 78g via opening 8g pass into a chamber 7g of the shut-off filtering means of the burette 75g and force the liquid sorbent 5g via an overflow means 6g into a first chamber 11g. In the process of contacting the liquid sorbent 5g, filtering materials 17g, 23g and sorbing materials 18g, the gases and vapors are decontaminated and, via opening 70g in a ground cone 68g and coupling 69g and along the

pipe 71g, are sucked out into the vacuum system.

After the burette 75g is filled, the opening in the coupling 69g is closed with the surface of the cone 69g by turning a handle 66g.

For removing the burette 75g from the cone 29e of the shut-off filtering device of the vessel 1e, said burette is turned through 90° until the opening 33e in the cone 29e is aligned with a conduit 80g in the coupling 78g (FIG. 20); at the same time, the interior spaces of a pipe union 77g of the burette 75g and of the central pipe 31e of the shut-off filtering device are filled with purified outside medium supplied from the second auxiliary chamber 36e through the opening 33e and conduit 80g until the inside pressure is balanced with that of the outside medium (the movement of the purified outside medium shown in FIG. 20 by arrow).

When emptying the burette 75g for the purpose of using the high-purity substance, the opening 70g in the cone 68g is aligned with that in the coupling 69g. When so doing, the outside medium (its movement shown by broken line) passes along the pipe 71g and through a circular clearance 72g into a first receptacle 21g of the shut-off filtering means of the burette 75g, and filters through the filtering materials 23g and sorbing materials 18g in its way down on the outer side of a cylinder 73g and then up on the inner side of the cylinder 73g, being purified from mechanical and chemical impurities. Passing up through a circular clearance 67g towards a top funnel 14g of the first chamber 11g of the second receptacle 12g, the purified outside medium forces the liquid sorbent 5g through an opening 9g, overflow means 6g and opening 4g into the last chamber 7g (the position of the liquid sorbent shown by broken line), is purified from the traces of impurities in the course of bubbling and, via the opening 8g, passes inside the burette 75g, balancing the pressure inside the latter with that of the outside medium. The high-purity substance to be used is fed under static pressure through the spout 76g.

FIG. 21 illustrates the shut-off filtering device of the vessel 1h, wherein a first receptacle 21h filled with filtering and sorbing materials is placed above a second receptacle 12h, chambers 7h and 11h of said second receptacle 12h being arranged in coaxial relation to each other.

The shut-off filtering device consists of an upper body 37h and lower body 43h, separated from each other by means of ridges 99h. The lower body 43h having a bottom 3h and a connecting sleeve 88h can be joined by a union 13h directly to the vessel 1h or to the neck 2h thereof, as shown in FIG. 22, or it can be made integral with the upper body 37h and constitute a single unit with the vessel 1h.

The body of the shut-off device is adapted to receive a shaped part 100 which is essentially a cylinder 101h with recesses 90h at the base and an outer partition 15h in the form of a rack with openings 14h adapted to be inserted into the ridges 99h and an inner partition 102h. In the center of the inner partition 102h there is provided a central connecting sleeve 38h in the form of a ground cone 29h with an opening 34h and an elongated end 103h threaded inside and outside, to which end there is hermetically joined from the inside a central pipe 31h, a ground cap 24h being screwed on said end from the outside.

Coaxial with the connecting sleeve 38h and above it on the inner partition 102h of the part 100h there is provided a circular sealing groove formed by a projection 84h on said part 100h, a circular sealing projection of the connecting sleeve 38h and an auxiliary pipe 41h.

To the central pipe 31h there is hermetically joined a leaf-type distributor 95h with a pipe 104h, forming together with the pipes 31h and 41h a hydraulic seal which precludes a direct communication of the high-purity substance with the outside medium through the opening 34h upon the removal of the cap 24h.

The open end of the upper body $37h$ can be closed hermetically on circular projections $105h$ by means of a shaped cover $83h$ having a central cylinder $82h$ with grooves $90h$ in the bottom portion and flanged edge $86h$ in the top portion, to which edge an aerosol filter $23h$ is secured by means of a thread $22h$.

The upper body $37h$ and the lower body $43h$ with the connecting sleeve $88h$, the cover $83h$ with the central cylinder $82h$, the shaped part $100h$ with the cylinder $101h$, rack $15h$, overflow means $6h$, inner partition $102h$, central connecting sleeve $38h$ and central pipe $31h$ form four intercommunicating circular chambers. The upper two chambers, $106h$ and $107h$, form a first receptacle $21h$. Into these latter chambers are charged sorbing materials $18h$. The chamber $106h$ is divided by means of partitions $19h$ into sections $20h$, while into the chamber $107h$ are placed filtering materials $17h$. The lower two spaces form first $11h$ and second $7h$ chambers of a second receptacle $12h$. The first receptacle $21h$ communicates with the outer medium through the openings $90h$ and cylinder $82h$, and with the second receptacle $12h$ —through the openings $14h$, while the chamber $7h$ of said second receptacle, in turn, communicates with the interior of the vessel $1h$ through an opening $8h$.

For the purpose of storing and transporting the high-purity substance in the vessel $1h$ without impairing the quality of said substance, the central pipe $31h$ is sealed hermetically by means of a film $30h$ secured by the thread $22h$ on the top end $103h$ of the cone $29h$; then, the cap $24h$ with a ground coupling $28h$ is set on the ground cone $29h$, thereby effecting the isolation of the opening $34h$ of a second auxiliary chamber $36h$ from the outside medium.

When the pressure inside the vessel $1h$ is reduced, the outside medium (its movement shown by arrow) passing through the filtering materials $23h$ to the interior space of the cylinder $82h$ is purified from mechanical impurities; upon having passed through the grooves $90h$, the outside medium enters the first receptacle $21h$ where it is purified from mechanical and chemical impurities with the aid of the sorbing materials $18h$ disposed in the chambers $106h$ and $107h$ of said first receptacle $21h$ and then with the aid of the filtering materials $17h$, whereupon said outside medium passes through the openings $14h$ into the second receptacle $12h$ in which it forces the liquid sorbent $5h$ through the grooves $90h$ of the overflow means $6h$ from the first chamber $11h$ into the chamber $7h$. The outside medium, which in the course of bubbling through the liquid sorbent $5h$ has been washed from the traces of impurities, passes through the opening $8h$ and along a clearance $91h$ to the interior of the vessel $1h$, whereby the pressure inside the latter is balanced with that of the outside medium.

In case the pressure inside the vessel $1h$ exceeds that of the outside medium, the gas-vapor mixture travels the above-described path in the reverse sequence (the movement of the gas-vapor mixture shown by broken arrow), that is, the gas-vapor mixture passing up through the clearance $91h$ enters through the opening $8h$ the last chamber $7h$ of the second receptacle $12h$ and forces the liquid sorbent $5h$ into the chamber $11h$ (the position of the liquid sorbent shown by broken line). Reacting with the liquid sorbent $5h$, filtering materials $17h$, sorbing materials $18h$, decontaminated gases leave through the filtering materials $23h$ into the outside medium.

FIGS. 23, 24, 25 and 26, 27, 28 illustrate the shut-off filtering device, as shown in FIG. 21, on which there is fitted an attachment $46i$ adapted for flushing the internal surface of the vessel $1h$ with a high-purity substance (FIGS. 23, 24, 25) and for filling said vessel $1h$ with the high-purity substance (FIGS. 26, 27 and 28).

The attachment $46i$ being essentially the attachment $46c$ described hereinabove in connection with FIGS. 4, 5, 6, 7, 8 and 9, presented hereinbelow is the description of only those elements of the attachment which take part in the operation of the shut-off filtering device when flush-

ing and filling the vessel $1h$ with a high-purity substance.

For the purpose of flushing the internal surface of the vessel $1h$, pressure is applied by means of the attachment $46i$ (or, on the contrary, by means of the vessel $1h$) through the cone $29h$ of the central connecting sleeve $38h$ onto the inner partition $102h$ of the shaped part $100h$, and the cone-shaped projection $84h$ forming a sealing groove sets down onto the connecting sleeve $88h$ and closes hermetically the opening $8h$. As a result of this closure, the interior of the vessel $1h$ is fully disconnected from the outside medium. Then, a plug $53i$ of a cock $51i$ is shifted to the position as in FIG. 24, which shows two sections XXIV—XXIV of the cock $51i$, defined by parallel planes in FIG. 23, conventionally turned through 90° . When so doing, the opening $34h$ is in the position shown in FIG. 25. In this position, the high-purity substance via manifold $58i$, conduit $56i$, plug $53i$, conduit $49i$ and opening $34h$ goes into the second auxiliary chamber $36h$ whence, filling conduits $97h$ and $96h$, it flows via conduit $91h$ onto the leaf-type distributor $96h$ and, with the latter's aid, is distributed over the walls of the vessel $1h$ (the movement of the high-purity substance shown in FIGS. 23 and 24 by arrow).

As the substance accumulates on the bottom $45h$ of the vessel, it is sucked in the form of a gas-vapor liquid emulsion along the central pipe $31h$ into a conduit $48i$ and, via the conduit in the plug $53i$ of the cock $51i$ and a conduit $55i$, enters a manifold $50i$ (the movement of the emulsion shown in FIGS. 23 and 24 by broken arrow).

FIG. 26 illustrates the shut-off filtering device according to FIG. 21, on which there is fitted (in the position shown in FIG. 28) the attachment $46i$ adapted for filling the vessel $1h$ with a high-purity substance.

Since the only difference of the filling process from the flushing one resides in the position of conduits in the plug $53i$ of the cock $51i$ with respect to conduits in a body 52 of said cock $51i$ (FIG. 28), all the reference numerals in FIGS. 23, 24 and 25 remain completely the same for defining the respective positions in FIGS. 26, 27 and 28.

For filling the vessel $1h$ with a high-purity substance, the plug $53i$ of the cock $51i$ is shifted, by turning it through 90° , into position as shown in FIG. 28. FIG. 28 shows two sections XXVIII—XXVIII of the cock $51i$, defined by parallel planes in FIG. 26, conventionally turned through 90° . The opening $34h$ is, at the same time, in the position as shown in FIGS. 23, 24, 25 and 26. In this position of the plug $53i$ and opening $34h$ the high-purity substance via the manifold $58i$, conduit $57i$, conduit in the plug $53i$ and conduit $48i$ goes along the central pipe $31h$ to the interior of the vessel $1h$, thus filling the latter (the movement of the high-purity substance shown in FIGS. 26 and 28 by arrow).

Air and vapors are sucked from the vessel $1h$ through clearances $91h$, $96h$ and $97h$, opening $34h$, along the conduit $49i$, conduit in the plug $53i$ and conduit $54i$ into the manifold $50i$ (the movement of gases and vapors shown in FIGS. 26 and 27 by broken arrow).

After the vessel $1h$ is filled with the high-purity substance, the pressure inside the central pipe $31h$ and vessel $1h$ should be balanced with that of the outside medium. To this end, the conduits $48i$, $49i$, $56i$ and $57i$ are closed from each other by means of the plug $53i$ of the cock $51i$; the attachment $46i$ is released and, by being turned through 90° , is shifted to the position as shown in FIG. 27; the compressed inner partition expands and, moving somewhat upwards, forms a circular opening $8h$ which effects the communication of the interior of the vessel $1h$ with the outside medium via the shut-off filtering device. As a result, the outside medium purified in accordance with the technique disclosed in the description of FIG. 21 passes via the clearances $8h$ and $91h$ to the interior of the vessel $1h$, and via the clearances $96h$, $97h$ (forcing, at the same time, the liquid sorbent $5h$ into the second auxiliary chamber $36h$), openings $34h$ and

61_h, conduits 63_i and 64_i enters the interior of the central pipe 31_h, thus balancing the pressure inside said vessel and central pipe with that of the outside medium.

FIG. 29 illustrates the shut-off filtering device, as shown in FIG. 21, on which there is fitted an attachment 65_k adapted for removing the high-purity substance from the vessel 1_h into a burette 75_k.

Since the attachment 65_k is essentially the attachment 65_d described hereinabove in connection with FIGS. 10 and 11, presented hereinbelow is the description of only those elements of the attachment which take part in the operation of the shut-off filtering device when removing the high-purity substance from the vessel or filling the latter with said high-purity substance.

In order to remove from the vessel 1_h the high-purity substance, the burette 75_k together with a ground coupling 78_k connected thereto is set onto the ground cone 29_h of the shut-off filtering device of the vessel 1_h. When so doing, a spout 76_k of the burette 75_k pierces the film 30_h and is received by the central pipe 31_h of the shut-off filtering device of the vessel 1_h. Thereupon, a vacuum line is connected to a pipe 71_k, and there takes place the evacuation of the interior spaces of the burette 75_k and of the central pipe 31_h through a shut-off filtering means of the burette 75_k. As a result, the outside medium purified in the shut-off filtering device of the vessel 1_h in a manner described hereinabove (cf. description of FIG. 21), after having passed inside the vessel through the opening 8_h and clearance 91_h, forces the contents of the vessel 1_h through the central pipe 31_h into the burette 75_k (the movement of gases and vapours of the high-purity substance into the burette 75_k shown in FIG. 29 by arrow).

Gases and vapors from the central pipe 31_h and the burette 75_k via opening 8_k pass to a last chamber 7_k of the shut-off filtering means of the burette 75_k and force the liquid sorbent 5_k via an overflow means 6_k into a first chamber 11_k. In the process of contacting the liquid sorbent 5_k, filtering materials 17_k, 23_k and sorbing materials 18_k, the gases and vapors are decontaminated and, via opening 70_k in a ground cone 68_k and coupling 69_k and along the pipe 71_k, are sucked out into the vacuum system.

After the burette 75 is filled, the opening in the coupling 69_k is closed with the surface of the cone 68_k by turning a handle 66_k.

For the purpose of removing the burette 75_k from the cone 29_h of the shut-off filtering device of the vessel 1_h, said burette is turned through 90° until the opening 33_h in the cone 29_h is aligned with a conduit 80_k in the coupling 78_k (FIG. 30); at the same time, the interior spaces of a pipe union 77_k of the burette 75_k and the central pipe 31_h of the shut-off filtering device are filled with purified outside medium supplied from the second auxiliary chamber 36_h through the opening 33_h and conduit 80_k until the inside pressure is balanced with that of the outside medium (the movement of the purified outside medium shown in FIG. 30 by arrow).

When emptying the burette 75_k for the purpose of using the high-purity substance, the opening 70_k in the cone 68_k is aligned with that in the coupling 69_k. When so doing, the outside medium (its movement shown by broken line) passes along the pipe 71_k and through a circular clearance 72_k into a first receptacle 21_k of the shut-off filtering device, and filters through the filtering materials 23_k and sorbing materials 18_k on its way down on the outer side of a cylinder 73_k and then up on the inner side of said cylinder 73_k, being purified from mechanical and chemical impurities. Passing up through a circular clearance 67_k towards a top funnel 14_k of the first chamber 11_k of the second receptacle 12_k, the purified outside medium forces the liquid sorbent 5_k through an opening 9_k, overflow means 6_k and opening 4_k into the chamber 7_k (the position of the liquid sorbent shown by broken line), is purified from the traces of impurities 75

in the course of bubbling and, via the opening 8_k, passes inside the burette 75_k, balancing the pressure inside the latter with that of the outside medium. The high-purity substance to be used is fed under static pressure through the spout 76_k of the burette 75_k.

FIG. 31 illustrates the shut-off filtering device of the vessel 1_l, secured on the neck 2_l of said vessel, in which device sections 20_l of a first receptacle 21_l filled with filtering materials 17_l and sorbing materials 18_l are placed 10 coaxial with chambers 7_l and 11_l of a second receptacle 12_l in which a liquid sorbent 5_l flows over.

The distinguishing feature of the present version of the shut-off filtering device according to the invention resides in that, when screwing a cover 83_l onto a body 115_l, the 15 shut-off filtering device is automatically brought into communication with the interior of the vessel 1_l owing to the fact that a sealing projection 84_l of the cover 83_l is lowered and disconnected from a sealing edge 110_l of the body 115_l.

When unscrewing the cover 83_l from the body 115_l, the sealing projection 84_l, going upwards, causes the sealing edge 110_l to wedge between said sealing projection and the neck 2_l of the vessel 1_l, thus breaking the communication of the interior of the vessel 1_l with the shut-off 25 filtering device and, consequently, with the outside medium.

The shut-off filtering device according to the present embodiment thereof consists of the body 115_l hermetically secured by means of a union 13_l to the neck 2_l of the vessel 1_l, the shaped cover 83_l adapted to be screwed onto the body 115_l, a screw-on cap 24_l, a central pipe 31_l, a through tip 108_l and a pipe 121_l adapted to be secured to the central pipe 31_l with the aid of a threaded bushing 120_l.

The body 115_l has a bottom 3_l with three concentrically arranged cylinders adjacent thereto: the outer cylinder defines said first receptacle 21_l and is provided on top with a screw thread 111_l designed for securing the cover 83_l and in the bottom portion, on the level of the inner plane of the bottom 3_l—with openings 113_l and a circular groove 112_l in which an aerosol filter 23_l is secured by means of threads 22_l; the middle cylinder is essentially a partition 15_l between the first receptacle 21_l and the second receptacle 12_l, provided with grooves 114_l serving for the passage of gases in case the cover 83_l comes into contact with said partition; the inner cylinder, 116_l, is provided with the inside circular sealing edge 110_l and with the union 13_l serving to secure the body 115_l to the neck 2_l of the vessel 1_l.

Into the circular groove between the outer and middle cylinders are placed the sorbing materials 18_l and filtering materials 17_l divided by partitions 19_l into the sections 20_l. Into the circular groove formed by the middle and inner cylinders is poured the liquid sorbent 5_l.

The body 115_l can be manufactured by the stamping technique.

Inside the cover 83_l adapted to be screwed onto the body 115_l provision is made of: two concentrically arranged cylinders, of which one, 117_l, is sunk into the sorbing materials and makes for the purification of the outside medium when passed through the union 111_l, while the other cylinder, 6_l, is essentially the overflow means of the second receptacle 12_l; concentrically arranged projections 109_l serving to ensure the passage of gases in case the cover 83_l comes into contact with the inner cylinder 116_l; a cylindrical pipe union 118_l terminating with a pipe 41_l and having the sealing projection 84_l on the level of the edge 110_l of the body 115_l.

From the outside of the cover 83_l, in the center thereof, provision is made of a countersunk central connecting sleeve 38_l in the form of a ground cone 29_l with an opening 34_l and an elongated ring 103_l threaded outside and inside, to which ring there is hermetically joined from the inside the central pipe 31_l and the tip 108_l.

sealing the latter, the ground cap **24l** being screwed on said end from the outside.

The cover **83l** and the cap **24l** can likewise be manufactured by die stamping technique.

The central pipe **31l** has a threaded end which can be retained in the vertical position, said end being instrumental in the adjustment of the value of a clearance **123l**; the lower end of said pipe is fashioned as a sleeve with a pipe **104l** and thick bottom **119l** in which there is secured by means of the bushing **120l** the pipe **121l**.

The through tip **108l** adapted to be screwed into the elongated end **103l** of the central connecting sleeve **38l** terminates in the bottom portion with a cone adapted to retain in place and seal (sealing **122l**) the central pipe **31l**. On top of the tip **108l** there is hermetically secured a film **30l** sealed by means of the thread **22l** wound thereon.

For the purposes of storing and transporting the high-purity substance in the vessel **1l** without impairing the quality of said substance, the tip **108l** or the elongated end **103l** of the central connecting sleeve **38l** is sealed hermetically by means of the film **30l** secured by the thread **22l** on the top end **103l** of the cone **29l**; then, the cap **24l** with a ground coupling **28l** is set on the ground cone **29l**, thereby effecting the isolation of the opening **34l** of a second auxiliary chamber **36l** from the outside medium.

When the pressure inside the vessel **1l** is reduced, the outside medium (its movement shown by arrow) passes through the filtering materials **23l** and opening **113l** into the first receptacle **21l** where it is purified from mechanical and chemical impurities with the aid of the sorbing materials **18l** and filtering materials **17l** disposed in the sections **20l**. Upon having passed through an opening **14l** to the first chamber **11l** of the second receptacle **12l**, the outside medium forces the liquid sorbent **5l** via the overflow means **6l** into the chamber **7l**. The outside medium, which in the course of bubbling through the liquid sorbent **5l** has been washed from the traces of impurities, passes through an opening **8l** and via clearance **91l** to the interior of the vessel **1l**, whereby the pressure inside the latter is balanced with that of the outside medium.

In case the pressure inside the vessel **1l** exceeds that of the outside medium, the gas-vapor mixture travels the above-described path in the reverse sequence (the movement of the gas-vapor mixture shown by broken arrow), that is, the gas-vapor mixture going up the clearance **91l** enters through the opening **8l** the chamber **7l** of the second receptacle **12l** and forces the liquid sorbent **5l** into the chamber **11l** (the position of the liquid sorbent shown by broken line). Reacting with the liquid sorbent **5l**, filtering materials **17l**, sorbing materials **18l**, decontaminated gases leave through the filtering materials **23l** into the outside medium.

FIGS. 32, 33, 34 and 35, 36, 37 illustrate the shut-off filtering device according to FIG. 31, on which there is fitted (in the position shown in FIG. 33) an attachment **46m** adapted for flushing the internal surface of the vessel **1l** with a high-purity substance (FIGS. 32, 33, 34) and for filling said vessel **1l** with the high-purity substance (FIGS. 35, 36 and 37).

The attachment **46m** being essentially the attachment **46c** described hereinabove in connection with FIGS. 4, 5, 6, 7, 8 and 9, presented hereinbelow is the description of only those elements of the attachment which take part in the operation of the shut-off filtering device when flushing and filling the vessel **1l** with a high-purity substance.

For the purpose of flushing the internal surface of the vessel **1l**, the cover **83l** is unscrewed from the body **115l** until the circular projection **84l** going upwards causes the sealing edge **110l** to wedge between said circular projection and the neck **2l** of the body of vessel **1l**. This done, there takes place the discontinuation of the communication of the interior of the vessel **1l** with the shut-

off filtering device and, consequently, with the outside medium.

Then, a plug **53m** of a cock **51m** is shifted to the position as in FIG. 33, which shows two sections **XXXIII-XXXIII** of the cock **51m**, defined by parallel planes in FIG. 32, conventionally turned through 90° . When so doing, the opening **34l** is in the position shown in FIG. 34. In this position, the high-purity substance via manifold **58m**, conduit **56m** of a body **52m**, plug **53m**, conduit **49m** and the opening **34l** passes into the second auxiliary chamber **36l** whence, filling conduits **97l** and **96l**, it is pulverized via clearance **123l** onto the internal surface of the vessel **1l** (the movement of the high-purity substance shown in FIGS. 32 and 33 by arrow).

As the substance accumulates on the vessel bottom **45l**, it is sucked in the form of a gas-vapor-liquid emulsion along the pipe **121l** and the central pipe **31l** into a conduit **48m** and, via the conduit in the plug **53m** of the cock **51m** and a conduit **55m**, enters a manifold **50m** (the movement of the emulsion shown in FIGS. 32 and 33 by broken arrow).

FIG. 35 illustrates the shut-off filtering device according to FIG. 31, on which there is fitted (in the position shown in FIG. 37) the attachment **46m** adapted for filling the vessel **1l** with a high-purity substance.

Since the only difference of the filling process from the flushing one resides in the position of conduits in the plug **53m** of the cock **51m** with respect to conduits in the body **52m** of the cock **51m** (FIG. 37) all the reference numerals in FIGS. 32, 33 and 34 remain completely the same for defining the respective positions in FIGS. 35, 36 and 37.

For filling the vessel **1l** with a high-purity substance, the plug **53m** of the cock **51m** is shifted, by turning it through 90° , into position as shown in FIG. 37. FIG. 37 shows two sections **XXXVII-XXXVII** of the cock **51m**, defined by parallel planes in FIG. 35, conventionally turned through 90° . The opening **34l** is, at the same time, in the position as shown in FIGS. 32, 33, 34 and 35.

In this position of the plug **53m** and opening **34l** the high-purity substance via the manifold **58m**, conduit **57m**, conduit in the plug **53m** and conduit **48m** goes along the central pipe **31l** and pipe **121l** to the interior of the vessel **1l**, thus filling the latter (the movement of the high-purity substance shown in FIGS. 35 and 37 by arrow).

Air and vapors are sucked from the vessel **1l** through clearances **123l**, **96l**, **97l**, opening **34l**, along the conduit **49m**, conduit in the plug **53m** and conduit **54m** into the manifold **50m** (the movement of gases and vapours shown in FIGS. 35 and 37 by broken arrow).

After the vessel **1l** is filled with the high-purity substance, the pressure inside the central pipe **31l** and vessel **1l** should be balanced with that of the outside medium, for the purpose of disconnecting the vessel **1l** from the attachment **46m**. To this end, the conduits **48m**, **49m**, **56m** and **57m** are closed from each other by means of the plug **53m** of the cock **51m**; the attachment **46m** (or the vessel **1l** with the shut-off filtering device) is shifted, by turning it through 90° , to the position as shown in FIG. 36; the cover **83l** of the shut-off filtering device is screwed onto the body **115l**, the circular projection **84l** goes down, gets disconnected from the sealing edge **110l** and effects via the conduits **8l** and **91l** the communication of the interior of the vessel **1l** with the shut-off filtering device and, consequently, with the outside medium. As a result, the outside medium purified in accordance with the technique disclosed in the description of FIG. 31 passes via the clearances **8l** and **91l** into the interior space of the vessel **1l**, and via the clearances **123l**, **96l**, **97l** (forcing, at the same time, the liquid sorbent **5l** into the clearance **97l**), openings **34l** and **62l**, conduits **63m** and **64m** enters the interior space of the tip **108l** and central pipe **31l** and of the pipe **121l**, thus balancing the pressure

inside the vessel and pipes with that of the outside medium.

FIGS. 38 illustrates the shut-off filtering device, as shown in FIG. 31, on which there is fitted an attachment 65n adapted for removing the high-purity substance from the vessel 1l into a burette 75n.

Since the attachment 65n is essentially the attachment 65d described hereinabove in connection with FIGS. 10 and 11, presented hereinbelow is the description of only those elements of the attachment which take part in the operation of the shut-off filtering device when removing the high-purity substance from the vessel or filling the latter with said high-purity substance.

In order to remove from the vessel 1l the high-purity substance, the burette 75n together with a ground coupling 78n connected thereto is set onto the ground cone 29l of the shut-off filtering device of the vessel 1l. When so doing, a spout 76n of the burette 75n pierces the film 30l and is received by the through tip 108l of the central pipe 31l of the shut-off filtering device of the vessel 1l. Then, a vacuum line is connected to a pipe 71n, and there takes place the evacuation of the interior spaces of the burette 75n, through tip 108l and of the central pipe 31l through a shut-off filtering means of the burette 75n. As a result, the outside medium purified in the shut-off filtering device of the vessel 1l in a manner described hereinabove (cf. description of FIG. 31), after having passed inside the vessel through the opening 8l and clearance 91l, forces the contents of the vessel 1l through the pipe 121l and central pipe 31l into the burette 74n (the movement of gases and vapours and of the high-purity substance into the burette 75n shown in FIG. 38 by arrow).

Gases and vapors from the central pipe 31l and the burette 75n via opening 8n pass to a chamber 7n of the shut-off filtering means of the burette 75n and force the liquid sorbent 5n via an overflow means 6n into a first chamber 11n. In the process of contacting the liquid sorbent 5n, filtering materials 17n, 23n and sorbing materials 18n, the gases and vapors are decontaminated and, via opening 70n in a ground cone 68n and coupling 69n and along the pipe 71n, are sucked out into the vacuum system.

After the burette 75n is filled, the opening in the coupling 69n is closed with the surface of the cone 68n by turning a handle 66n.

For the purpose of removing the burette 75n from the cone 29l of the shut-off filtering device of the vessel 1l, said burette is turned through 90° until the opening 33l in the cone 29l is aligned with a conduit 80n in the coupling 78n (FIG. 39); at the same time, a pipe union 77n, the interior space of the burette 75n and the central pipe 31l of the shut-off filtering device of the vessel 1l are filled with the purified outside medium supplied from the second auxiliary chamber 36l through the opening 33l and conduit 80n until the inside pressure is balanced with that of the outside medium (the movement of the purified outside medium shown in FIG. 39 by arrow).

When emptying the burette 75n for the purpose of using the high-purity substance, the opening 70n in the cone 68n is aligned with that in the coupling 69n. When so doing, the outside medium (its movement shown by broken line) passes along the pipe 71n and through a circular clearance 72n into a first receptacle 21n of the shut-off filtering device, and filters through the filtering materials 23n and sorbing materials 18n on its way down on the outer side of a cylinder 73n and then up on the inner side of said cylinder 73n, being purified from mechanical and chemical impurities. Passing up a circular clearance 67n towards a top funnel 14n of the first chamber 11n of the second receptacle 12n, the purified outside medium forces the liquid sorbent 5n through an opening 9n, overflow means 6n and opening 4n into the chamber 7n (the position of the liquid sorbent shown by broken line), is purified from the traces of impurities in the course of bubbling and, via the opening 8n, passes inside the burette 75

75n, balancing the pressure inside the latter with that of the outside medium. Further, the high-purity substance is fed under static pressure through the spout 76n of the burette 75n for being used.

I claim:

1. A filtering device comprising a vessel, means for defining first and second receptacles in communication with one another, said first receptacle including filtering means extending thereacross and at least two different solid sorbing materials also extending thereacross, said first receptacle having an opening exposing said filtering means and solid sorbing materials to the atmosphere, means dividing said first receptacle into a plurality of communicating sections for separating said different solid sorbing materials from one another, said second receptacle including a liquid sorbing material at the bottom thereof in spaced and exposed relation with said solid sorbing materials in said first receptacle, means for maintaining the sorbing materials in said receptacles respectively in spaced communicating relation through the interior of said second receptacle, means for defining a first chamber externally of said second receptacle and communicating the interior of the vessel with the interior of the second receptacle, means for dividing said second receptacle into second and third chambers, and overflow conduit means in said third chamber for communicating said second and third chambers with one another such that said liquid sorbing material flows therebetween in response to the difference in pressure between the atmosphere and the interior of the vessel.

2. A shut-off filtering device according to claim 1, arranged outside said vessel and having a protective cap with a cone-shaped ground surface in contact with the ground surface of the neck of said vessel.

3. A shut-off filtering device according to claim 1, wherein said sections filled with said filtering and sorbing materials are positioned above said chambers in which flows the liquid sorbent.

4. A shut-off filtering device according to claim 1, wherein said sections filled with said filtering means and solid sorbing materials are arranged coaxial with said chambers in which said liquid sorbent flows over.

5. A shut-off filtering device according to claim 4, wherein for the purpose of disconnecting the interior of the vessel from said receptacles and from the outside medium, the upper end of the overflow means is provided with a ground surface mating with a corresponding ground surface of a connecting sleeve of the vessel neck by way of mutual axial displacement of said overflow means and said connecting sleeve of the vessel neck in the course of flushing and filling said vessel.

6. A shut-off filtering device according to claim 4, wherein said sections of said first receptacle, filled with the filtering and sorbing materials, are positioned above said second receptacle in which the chambers with the liquid sorbent flowing therein are arranged coaxially.

7. A shut-off filtering device according to claim 4, wherein for the purpose of disconnecting the interior of the vessel from said receptacles and from the outside medium, said connecting sleeve of the vessel neck terminates with a circular sealing projection connectable by way of mutual axial displacement with a projection of a part and with an auxiliary pipe when flushing and filling said vessel.

8. A shut-off filtering device according to claim 4, whose body has flanged edges and a cover with a circular projection, which are mated with each other and with the neck of the vessel during the mutual turn of said cover and said body when flushing and filling the vessel, for isolating the interior of said vessel from said receptacles and from the outside medium.

9. A shut-off filtering device according to claim 1, wherein the third chamber of said second receptacle is connected to the outside medium via the first chamber, the latter being formed by the central pipe of a central

25

connecting sleeve with openings, which central pipe passes through said chambers and said sections of the receptacles, without reaching the bottom of the vessel, and is connected to the internal conical wall of said connecting sleeve by means of an auxiliary pipe which is arranged coaxial with the sleeve and divides the interior of the latter into a first auxiliary chamber and a second auxiliary chamber, said second auxiliary chamber being formed by said auxiliary pipe and the conical wall of said connecting sleeve.

10. A shut-off filtering device according to claim 9, which is arranged inside said vessel.

11. A shut-off filtering device according to claim 9, wherein, for the purposes of transporting and storing substances, onto the conical outer surface of the central connecting sleeve there is fitted a removable cap serving to isolate said auxiliary chambers from the outside medium and to communicate via an opening said first auxiliary chamber with said second auxiliary chamber, which latter chamber receives through an opening the purified outside medium directed via an opening into the interior of said vessel through a hydraulic seal formed by the clearance between said auxiliary pipe and said central connecting sleeve, clearance between the walls of the lower and upper bodies of the device, and pipes serving to interconnect said clearances, said hydraulic seal serving to isolate the interior of said vessel from the outside medium.

12. A shut-off filtering device according to claim 9, wherein for the purposes of storing and transporting substances, onto said conical outer surface of the central pipe of the central connecting sleeve there is fitted said removable cap serving to isolate said second auxiliary chamber from the outside medium.

13. A shut-off filtering device according to claim 9, wherein, for the purposes of flushing the internal surface of said vessel and filling the latter with a substance, onto said conical outer surface of the central pipe of the central connecting sleeve there is fitted an attachment including a bypass cock and a coupling connected thereto and adapted to isolate said first auxiliary chamber from the outside medium and from said second auxiliary chamber connected to the bypass cock which, in its turn, is connected to the inlet end of said central pipe.

14. A shut-off filtering device according to claim 13, wherein, for the purposes of flushing the internal surface of said vessel and filling the latter with a substance, onto said conical outer surface of the central pipe of the central connecting sleeve there is fitted said attachment including a bypass cock and a coupling connected thereto and adapted to isolate from the outside medium said second auxiliary chamber connected by means of a side pipe

26

with the bypass cock which, in its turn, is connected to the inlet end of said central pipe.

15. A shut-off filtering device according to claim 9, wherein, for the purposes of removing substances from the vessel and using them, onto said conical outer surface of the central pipe of the central connecting sleeve there is fitted an attachment including a calibrated burette with a shut-off filtering means, to which burette there is connected a pipe union with a coupling, said coupling serving to isolate said auxiliary chambers from the interior of said central pipe and connect both said auxiliary chambers to each other and to the interior of said vessel.

16. A shut-off filtering device according to claim 15, wherein, for the purposes of removing substances from said vessel and using them, onto said conical outer surface of the central pipe of the central connecting sleeve there is fitted said attachment including a calibrated burette with a shut-off filtering means, to which burette there is connected a pipe union with a coupling, said coupling serving to isolate said second auxiliary chamber from the interior of said central pipe.

17. A shut-off device as claimed in claim 1 wherein said means for dividing said first receptacle includes a plurality of spaced parallel partitions.

18. A shut-off device as claimed in claim 17 including a plurality of porous containers containing said different solid sorbing materials respectively in a prescribed pattern.

19. A shut-off device as claimed in claim 18 wherein said porous containers are bags.
